Fig. 6.

Fig. 7.

Fig. 8.

FIG. 1 is a top plan view of a photographic van embodying my new design, with the front bumper platform in the extended position and with the doors in open position;

FIG. 2 is a front elevational view thereof taken from the left of FIG. 1;

FIG. 3 is a rear elevational view thereof taken from the right of FIG. 1;

FIG. 4 is an enlarged left side view thereof, in perspective, with the front bumper platform in the retracted position;

FIG. 5 is an enlarged right side view thereof, in perspective, also with the front bumper platform in the retracted position;

FIG. 6 is a left side elevational view of the photographic van with the doors in the closed position;

FIG. 7 is a rear elevational view thereof, also with the doors in the closed position; and

FIG. 8 is a right side elevational view thereof, also with the doors in the closed position.

The elements shown in broken lines are included for illustrative purposes only.

I claim:

The ornamental design for a photographic van, as shown and described.
